David H. Rice

UNITED STATES PATENT OFFICE.

DAVID HALL RICE, OF LOWELL, ASSIGNOR TO JAMES FERGUSON, OF BRIDGEWATER, MASSACHUSETTS.

CAR-WHEEL.

SPECIFICATION forming part of Letters Patent No. 330,423, dated November 17, 1885.

Application filed January 3, 1885. Serial No. 151,900. (No model.)

To all whom it may concern:

Be it known that I, DAVID HALL RICE, of Lowell, in the county of Middlesex and State of Massachusetts, have invented a new and 5 useful Improvement in Car-Wheels, of which the following is a specification.

My improvement relates to car-wheels; and it consists in a novel method of combining the parts of a wrought-iron car-wheel body to form 10 therefrom a solid and substantial wheel-body without the use of bolts or rivets to hold the parts together, substantially as hereinafter described and claimed.

In the drawings, Figure 1 represents a face 15 or side view of a car-wheel body constructed according to my invention. Fig. 2 is a transverse section through the axis of the wheel-body. Fig. 3 represents a transverse sectional view of the wheel-blanks before the 20 rim is attached thereto, with the appliances used to aid in forging on the rim. Figs. 4 and 5 are views of the opposite faces of the piece of iron used to form the rim before it is built up on the wheel-blanks, as hereinafter 25 described. Fig. 6 is a transverse section of Fig. 4 on the line $x x$.

To form the wheel-body, I take two wrought-iron blanks, A A, which are to be made substantially in the manner described in the Letters 30 Patent granted to James Ferguson, October 7, 1884, No. 306,070. These blanks are formed with an annular lip, $a a$, around each, as described in said Ferguson patent, and with annular shoulders $a' a'$ in their outer faces. I mount 35 these blanks on an axle, B, and on the outside of each I place a metal supporting-piece, D D, fitted to go under the shoulders $a' a'$ and support the outer parts of the disk in position. These supporting-pieces are disks fitted to the 40 form of the blanks on their faces, and they slip over the shaft B and are clamped up against the wheel-blanks by nuts $d d$, working into screw-threads on the shaft B.

E is a base or foundation supporting two 45 uprights, $e' e'$. At their upper ends these uprights have slots or notches vertically and centrally across them, into which the ends of the axle B can be dropped, as shown in Fig. 3, and allow it to revolve in them. Mounted in 50 the uprights $e' e'$, as shown, is a metal roller

F, on an axle, F', which revolves in bearings in the uprights, and has a pulley, F², on its end to give it motion from any suitable counter-shaft. The roller F is made of a shape the reverse of the edges of the wheel-blanks A A, 55 as shown. I next prepare a strip of metal, S, long enough to wind a sufficient number of times around the edges of the wheel-blanks to make the rim of the wheel, and I roll this strip with a groove, s, on one side which will 60 just fit over the annular lips $a a$ of the blanks, and on the opposite side of the strip S, I roll a rib of the same breadth and height as the two lips $a a$.

Having thus prepared the several parts, I 65 place the two wheel-blanks A A on the axle B in a furnace and bring the heat of the furnace upon the edges of the blanks and the lips $a a$ until they are heated to a welding-heat. For this purpose I employ a furnace having 70 an annular fire-chamber of the proper size—such, for instance, as the furnace patented to said James Ferguson, October 7, 1884, No. 306,071—or any other well-known annular chambered furnace. At the same time I heat 75 the strip of metal S to a welding-heat in another furnace. I then take the wheel-blanks and axle out of the furnace and drop the axle into the notches in the standards $e' e'$, and introduce the end of the strip S between the 80 roller F and the edges of the blanks, so that the groove s will embrace the lips $a a$, when, by giving motion to the roller F, the strip will be continually rolled and welded upon the edges of the blanks A A and upon itself 85 until the rim of the wheel is formed. I then turn off the exterior of the rim to any form desired to receive the tire. It is understood, of course, that the notches in the ends of the uprights shall be made deep enough to allow 90 the axle to rise as the successive layers of the rim are thus built upon it, and weights or pressure may be applied on top of the axle to give the requisite pressure upon the welding-roll F, if the weight of the blanks and their 95 supporting-disks D D are not sufficient. It is also obvious that with a light or thin strip, S, the supporting-disks D D may be dispensed with and the edges of the wheel-blanks A A be temporarily held together by bolts or rivets, 100

as shown in said Ferguson patent, while the welding of the rim is accomplished; or the blanks may be driven so firmly onto the axle B as to thus hold them together, the essential 5 feature of my invention being the coiling and welding of the continuous strip S around and upon the edges of the blanks A A and upon itself to form the rim of the wheel and unite the blanks together. It is also obvious that 10 the strip S may be made flat and the lips *a a* be omitted from the wheel-blanks and the strip welded on, as described; or the lips may be omitted and the groove *s* and strip S be made wide enough to embrace the entire edges 15 of the blanks A A without departing from the spirit of my invention. In case a tire is to be placed on the rim of the wheel requiring an annular holding-groove for it in the rim, I form this groove while welding up and forming 20 the rim in the following manner: Near one end of the strip S, I cut a piece out of one side of it, between *s²* and *s³*, of the proper depth and of a length to extend either entirely or partially round the wheel. Between *s³* and 25 *s⁴*, which is of the length to reach at least round the wheel over the last-mentioned cut-away part, I cut away the side of strip S to a less depth inward. I coil and weld this cut-away end of the strip around the wheel-blanks 30 and itself last. The cut-away portion between *s²* and *s³* will thus form a recessed portion or groove, *c*, in the edge of the rim, and the portion between *s³* and *s⁴* will form a lip overhanging the groove *c*, as shown in Figs. 1 and 2. 35 The tongue *s'* being turned off of the outer edge of the finished rim, the tire may be fitted to this outer edge and into groove *c*.

Instead of employing the roller F to weld on the successive layers of the rim, it may be 40 welded by any other suitable means—as, for instance, by hand—as the coiling progresses.

One great advantage in forming the rim of the wheel as above described is that, as it 45 consists of several layers of iron welded upon each other, as described, the imperfections of the metal in one part of the strip, if any happen to occur, are neutralized by the perfect parts welded against them, and cannot affect the entire rim, as appears in Fig. 2, where the

dotted lines represent the several layers welded together. The rim made in this way is also not liable to expand like a single piece or thickness of metal. 50

What I claim as new and of my invention is— 55

1. The hollow wrought-iron car-wheel body, formed of the blanks A A and a wrought-iron rim coiled and welded together and upon the edges thereof from a strip of metal, S, in successive layers, substantially as described. 60

2. The hollow wrought-iron car-wheel body, formed of the blanks A A and a wrought-iron rim coiled and welded upon the edges thereof from a strip, S, provided with a groove, *s*, which embraces a portion of said blanks during 65 the welding process, substantially as described.

3. The combination of the blanks A A, provided upon their edges with the lips *a a*, and the strip S, provided with the groove *s*, embracing said lips and coiled and welded thereon, the whole forming a car-wheel body, substantially as described. 70

4. The combination of the blanks A A, provided upon their edges with the lips *a a*, and the strip S, provided with the groove *s* and rib *s'*, and coiled and welded upon said lips and upon itself, substantially as described. 75

5. The combination, with the blanks A A, of the strip S, having a portion between *s²* and *s³* cut away from its side to a greater depth 80 than the metal on either side of it, and coiled and welded upon said blanks and itself, forming the rim of the wheel-body and the groove *c* therein in the same operation, substantially as described. 85

6. The combination, with the wheel-blanks A A, of the strip S, having a portion between *s³* and *s⁴* cut away from its side upon one end and coiled and welded upon said blanks and itself, forming a shouldered or offset part at 90 the outer edge of the rim, substantially as described.
